UNITED STATES PATENT OFFICE.

FELIX WYNER, OF NEW YORK, N. Y., ASSIGNOR TO PHENIX CHEESE COMPANY, A CORPORATION OF NEW YORK.

FOLDING MECHANISM FOR PACKAGING MACHINES.

Application filed January 25, 1922. Serial No. 531,599.

To all whom it may concern:

Be it known that I, FELIX WYNER, a citizen of the United States, a resident of New York, in the county of Bronx and State of New York, have invented certain new and useful Improvements in Folding Mechanisms for Packaging Machines, of which the following is a full, clear, and concise description.

10 My invention relates to folding mechanisms for packaging machines, and more particularly to the kind of folding mechanisms adapted for use upon machines for packaging plastic materials, such as cheese, 15 butter, lard and the like.

Stated more specifically, my invention relates to mechanisms for folding a wrapper about a cake of the plastic material to be packaged, these mechanisms being used in 20 connection with other devices, and all being employed together for the purpose of producing packages adapted for commercial use.

A prominent feature of my invention is 25 a plurality of folder arms and a package wrapping platform associated with said folder arms, and suitable mechanism for shifting the folder arms one at a time relatively to the platform, so that with a wrapper resting upon the platform and a cake of plastic material resting upon the wrapper, first one edge of the wrapper is folded in 30 one direction over the cake, by a movement of one of the folder arms, and then a different edge of the wrapper is folded in a 35 different direction over the cake, by the movement of a different folder arm. Thus the last-mentioned edge of the wrapper is caused to overlap the first-mentioned edge 40 thereof. By this arrangement, one edge of the wrapper is folded down upon the cake of plastic material and rendered stationary before the opposite edge is brought over it, and the oppositely-disposed edges of the 45 wrapper are prevented from clashing together or otherwise interfering each with the other.

A typical substance upon which my improved folding mechanism may be used for 50 packaging is cream cheese, but my invention may be employed to advantage in packaging almost any material to be enclosed in separate individual foldable wrappers, such as sheets of tin foil or paper.

Reference is made to the accompanying 55 drawings forming a part of this specification, and in which like reference characters indicate like parts throughout the several figures.

Figure 1 is a view, partly in plan and 60 partly in section, of a packaging machine equipped with a number of package wrapping platforms each having associated with it one of my improved folding mechanisms.

Figure 2 is a fragmentary plan of one of 65 the package wrapping platforms, carrying my improved folding mechanism.

Figure 3 is a section on the line 3—3 of Figure 2, looking in the direction indicated by the arrows. 70

Figure 4 is a section on the line 4—4 of Figure 2, looking in the direction indicated by the arrows.

Figure 5 is a perspective of a double track cam used in connection with mechanism for 75 actuating the folder arms forming a part of my invention.

Figures 6 to 15 inclusive are diagrams, indicating one of the package wrapping platforms and various movable parts immediately associated therewith as used for placing a wrapper upon a cake of cheese or the like, the several figures indicating the various successive positions of the movable parts at different stages of the work of folding the wrapper upon the cake. 85

A table is shown at 16, and supports a feed hopper 17, containing a revoluble feed screw 18, for agitating and exerting pressure upon a plastic material to be contained 90 in the feed hopper. Connected with the feed hopper 17 and supported by the table 16 is a feed mechanism 23, for forming the plastic material into the cakes which are to be wrapped, as hereinafter described. 95

Mounted over the table 16 is a turntable 24, having a step-by-step revoluble movement. A power shaft 25 is used for conferring movements upon various movable parts, including the turntable 24. The 100 power shaft 25 carries a pulley 26 whereby it is actuated.

The turntable 24 is provided with a number of holes, one of which is shown at 27 in Figure 4. These holes are exactly alike, and 105 are spaced equidistant. Covering each hole 27 is a base 28, detachably secured upon the turntable by bolts 29 and carrying a

hollow frame 30, this frame having a reduced portion 31, extending downwardly and through the hole 27, as may be understood from Fig. 4. The frame 30 is further provided with bearings 31, extending upwardly. Supported by these bearings are a pair of folder arms 32, 33, the folder arm 32 being mounted rigidly upon a shaft 34, and the folder arm 33 being similarly mounted upon a shaft 35. The shafts 34 and 35 are supported in part by the bearings 31 and in part by another pair of bearings 36, shown more particularly in Figure 2. Each folder arm 32, 33 is adapted to rock within definite limits of travel.

The rocking movements of the two folder arms are performed, however, at slightly different moments; each movement of the folder arm 32, in either of two directions, preceding the corresponding or similar movement of the folder arm 33. That is to say, reckoning from the direction of step-by-step travel of the turntable, as indicated by the arrow in Figure 1, the folder arm 32, which is the one in front, acts a trifle earlier than the other folder arm 33 of the same pair.

For the purpose of actuating the shafts 34, 35 I provide them with pinions 37, 38, secured rigidly upon them.

Disposed adjacent the pinions 37, 38, and located below the same are a pair of sliding bars 39, 40, provided respectively at their upper ends with portions 41, 42 formed into racks, as shown in Figure 3, these racks engaging the pinions 37, 38 in such manner that the sliding movements of the bar 39, 40 will cause the racks to turn the pinions in opposite directions. The sliding bars 39, 40 are mounted in bearings 43, 44, shown more particularly in Figure 3. A tensile spring 45 is connected with the sliding bar 39 and with the bearings 45, another tensile spring 46 being similarly connected with the sliding bar 40 and with the bearing 44. The tensile springs 45, 46 are always under tension, and because of this fact they have a tendency to force the sliding bars 39, 40 downwardly each in the direction of its length, as may be understood from Figure 3. The bearings 43, 44 are here shown as made in a single piece mounted upon base 47, this base being detachably secured upon the turntable by means of bolts 48, as may be understood from Figure 2, and extending through a hole 51 in the turntable as indicated in Figure 3. The sliding bar 39 carries upon its bottom end a roller 49, a similar roller 50 being mounted upon the bottom end of the sliding bar 40.

Located below the turntable 34 is a stationary cam ring 52, provided with a pair of cam walls 53, 54, as shown more particularly in Figure 5. The cam wall 53 extends upwardly from the cam ring, and is concentric

to the cam wall 54 which extends upwardly from the outer edge thereof. The cam wall 53 is partially cut away as indicated in Figure 5, so as to present a pair of inclined portions 55, 56 and a connecting intermediate portion 57, this last-mentioned portion being quite low as compared with the top edge of the cam wall. The cam wall 54 is provided with a single depression 58, as indicated more particularly in Figure 5.

The cam wall 53, with its depressed portion 57, is engaged periodically, during the action of the machine, by the rollers 49, 50, above described as mounted upon the sliding bars 39, 40. That is to say, each roller 49, 50 runs upon the inner cam wall, and is at all times in engagement with some part of the top thereof. For this purpose the cam wall in question may be considered as practically a track, upon which rollers 49, 50 are arranged to run in tandem, each of these rollers being alternately raised and lowered in consequence of the conformity of the cam wall as above described. Since the cam wall in question is fixed in position and the rollers 49, 50 move relatively to it, the roller 49 being in front, it necessarily follows that whenever the roller 49 moves either upwardly or downwardly, the roller 50 must immediately thereafter execute a similar movement. Thus the sliding bars 39, 40 must cause the shafts 34, 35 to execute rocking movements so arranged that any movement conferred by the shaft 34 upon the folder arm 32 is followed an instant later by a similar movement, conferred upon the folder arm 33 by the shaft 35. These successive movements of the folder arms 32, 33 take place whenever these arms move into the positions indicated for them in Figure 4, or out of such positions and into the positions indicated for them in Figure 2. The purpose in thus causing the folder arms 32, 33 to move in successive order, as stated, is to properly manipulate the wrapper relatively to the cheese cake, as hereinafter more completely described.

Extending through the frame 30 and movable bodily in relation thereto is a sliding bar 59, having a form which may be understood by reference to Figure 4. The upper end of this sliding bar is provided with two sets of rack teeth 60, 61 formed upon opposite edges of the bar and thus disposed oppositely to each other.

These two sets of rack teeth engage respectively two pinions 62, 63, these pinions being secured rigidly upon two shafts 64, 65 extending horizontally and adapted to rock in opposite directions. The shafts 64, 65 are supported upon the hollow frame 30.

Mounted upon the shaft 64 are a pair of folder fingers 66, and similarly mounted upon the shaft 65 are another pair of folder fingers 67.

130

The pair of folder fingers 66 have, under control of the shaft 64, two normal positions; and the pair of folder fingers 67, under control of the shaft 65, have likewise two normal positions. The respective normal positions of the different folder fingers are indicated in Figure 4 by full and broken lines.

The sliding bar 59 carries a roller 68, 10 which engages and runs upon the cam wall 54—that is, the outer cam wall according to Figure 5.

A sliding bar 59^a is carried by the frame 30, and is disposed upon the side thereof 15 opposite the sliding bar 59, as may be understood from Figure 2. The sliding bar 59^a does not carry any roller like the roller 68 with which the sliding bar 59 is provided. Otherwise, the sliding bar 59^a and its im- 20 mediate connections are like the sliding bar 59 and its immediate connections.

By means of two tensile springs 69, 70 connected with the respective sliding bars 59, 59^a, these sliding bars are always under 25 tension, so that they are thrust downward. Simultaneously each time the roller 69 enters the depression 58, as may be understood from Figure 4.

Whenever the frame 30, carried by the 30 turntable, passes over the depression 58 in the cam wall 54, as indicated in Figure 4, the sliding bar 59 makes a thrust downwardly which is quite abrupt and rapid, and then rises, a little more slowly, to its original 35 position, as may be understood from Figure 4. This means that all of the folder arms 66, 67, as a gang, quickly assume one position; and then as a gang but a little more slowly, assume a different position.

40 The parts are so arranged and co-related as to act in sequence as follows: First, the folder arm 32 swings upwardly and into the position indicated for it in Figure 8, and a moment later the folder arm 33 moves into 45 the position indicated for it in Figure 9; next all four of the folder fingers 66, 67 swing upward simultaneously as indicated by dotted and full lines in Figure 10; and then the four folder fingers all swing downward simultaneously; as indicated in Figure 11; afterward, the folder arm 32 swings downwardly as indicated in Figure 13, and the next moment the folder arm 33 also swings downwardly. The various steps just 55 mentioned are repeated, in the successive order just stated, each time the turntable travels a step in its step-by-step movement above described.

A cake of plastic material, such as cream 60 cheese, just discharged by the feeding mechanism 23, is shown as resting upon a wrapper 72 at the top of Figure 1. Two of these wrappers are shown in this figure, one of them appearing as partly broken away. 65 The wrappers may be made of any suitable

sheet material, such for instance as tin foil. A pile of the wrappers are shown at 73, contained in a wrapper magazine 74.

A vacuum plate 75 is provided for picking up the wrappers one at a time from the 70 wrapper magazine 74, and placing them upon the several package wrapping platforms as the latter, carried by the turntable and therewith actuated step-by-step, are successively brought into proximity to the 75 magazine. The vacuum plate 75 is provided with suction cups 76, shown more particularly in Figure 6, for the purpose of enabling the vacuum plate to lift, carry and deliver the wrappers one at a time. A flexible pipe 77 is connected with the vacuum plate 75, for the purpose of controlling the vacuum therein. The vacuum plate is mounted upon a swinging arm 78, and under 80 control of the latter is movable back and 85 forth, for the purpose of transferring the wrappers as just explained.

Mechanism 79 is provided for actuating the arm 78 and thus controlling bodily movements of the vacuum plate, relatively 90 to the general position of the turntable.

Connected with the mechanism 79 is a swinging arm 80 which is also connected with ejector mechanism 81, the latter being provided with a hook 82 for the purpose of 95 removing the finished packages one at a time, as they arrive in succession and in position for this purpose, as may be understood from Figure 1.

The hollow frame 30 carries a bed 83, 100 provided with a facing 84, this facing being provided with holes 85. A pipe 86 is connected with the bed 83, and by aid of this pipe a partial vacuum is periodically created and destroyed in the space between the bed 83 and the facing 84. In the particular instance here shown there are six of these pipes 86, as may be understood from Figure 1. By means of a movable vacuum ring 87, to which the pipes 86 are connected and a vacuum ring 88 to which is connected a 105 vacuum pipe 89, the pipe 89 is effective for removing air from the pipes 86 and parts connected therewith, for the purposes herein contemplated.

110 The mechanism just described is adapted to periodically create and destroy a partial vacuum below each facing 84.

Thus essentially the mechanism just described is a pneumatic holdfast for holding wrappers upon the facings 84, and releasing the same. The purpose is to hold each wrapper firmly in position while the cake of plastic material is placed upon it, and while each wrapper is being folded around the cake 115 resting upon it.

A pair of smoothing blades 90, carried by a plunger 91, are so mounted that while they have a slight vertical movement, the general position they occupy is stationary as 120 125 130

considered relatively to the movement of the turntable. Another pair of smoothing blades 93 have each a slight vertical movement, but the general position occupied by these two smoothing blades is also stationary as regards the turntable.

A yoke 94, shown more particularly in Figure 4, is used for actuating the smoothing blades 93 in unison.

- 10 Thus there are two pairs of smoothing blades, each pair having a slight vertical movement relatively to the turntable. The smoothing blades, thus arranged in pairs, are for the purpose of smoothing or pressing down certain portions of the wrapper after the wrapper is folded around the cheese cake.

The several successive positions assumed by each package wrapping platform, incidental to the step-by-step movement of the turntable, and indicated upon Figure 1 by the letters A, B, C, D, E and F, are closely associated with the successive diagrams shown in Figures 6 to 15 inclusive. That is to say, Figure 6 indicates the condition of any particular package wrapping platform and various movable parts associated therewith, when the platform stops in the position indicated for it at A. Figure 7 indicates the condition of the same platform when it stops in the position indicated at B. Figure 8 indicates the condition of the platform and the position assumed by various movable parts carried by it, while the platform is in motion and traveling from the position B to the position C, as indicated by the arrow in Figure 8. Figure 9 indicates the condition of the platform and parts immediately associated with it, when the platform stops in the position C. As the platform is traveling from its position C to the position D, as indicated by the arrow in Figure 10, various movable parts carried by the platform execute movements indicated by full dotted lines and broken lines in Figure 10. When the platform stops in the position D, however, as indicated in Figure 11, all movable parts carried by it are at rest in the position indicated for them in this Figure. When the platform moves into the position E and stops, certain movable parts carried by the platform are thereupon caused to execute movements in sequence with movements of other parts not carried by the platform, as indicated in the two Figures 12 and 13. While the platform is in motion traveling from the position E to the position F as indicated by the arrow in Figure 14, certain movable parts carried by the platform are actuated, as indicated in this figure. When the platform stops in the position F, the movable parts carried by it are stationary, but the ejector mechanism, which is mounted independently of the platform but in suitable

position to coact therewith, is actuated for the purpose of removing the finished package.

The operation of my device is as follows:

I will assume that the various parts are assembled and arranged as above described; that by appropriate means a partial vacuum is created and maintained in each of the air pipes; that a supply of cheese or other plastic material has been provided, and placed in the feed hopper; that the wrapper magazine is filled with wrappers; and that the various movable parts are being actuated, as described.

A single wrapper is picked up by the vacuum plate 75, and deposited upon the nearest adjacent package wrapping platform as indicated at 72 in Figure 1. The platform in question now occupies the position A. The middle of this wrapper is held tightly in position, by means of the pneumatic holdfast above described.

As the platform moves one more step it is brought into the position B, and the wrapper just mentioned is brought into proximity to the feed mechanism 23, which delivers a cake of plastic material 71 and places it centrally upon the wrapper, as shown.

The turntable now moves another step, and the platform stops in the position C. While the turntable is moving the platform in question from the position B to the position C and thus while it is in motion, as indicated by the arrow in Figure 13, the folder arms 32, 33 are moved one at a time, in the manner above described. That is to say the folder arm 32 swings up over the adjacent portion of the cake of plastic material, and in so doing bends over the cake the adjacent portion of the wrapper. This is followed by the upward swing of the folder arm 33, this folder arm, in executing its movement, carrying with it the adjacent portion of the wrapper 72 so as to cause it to overlap that portion of the wrapper previously placed in position by the movement of the folder arm 32. This leaves the folder arms 32, 33 and various other movable parts in the positions indicated for them in Figure 9.

The next step in the movement of the turntable carries the platform from the position C to the position D. While the platform is thus traveling, as indicated by the arrow in Figure 10, the folder fingers 66, 67 initially occupying their lowermost positions as indicated in Figure 8, spring up into the positions indicated for them by full lines in Figure 10, and dropped back into their initial positions indicated by broken lines in this figure, so that when the platform stops in the position D the various parts appear as indicated in Figure 11.

Another step of the turntable brings the platform into the position indicated at E, 130

and thus into proximity to the smoothing blades 90, 90, 93, 93, which are so actuated as to smooth various parts of the wrapper, as may be understood from Figures 12 and 13.

The platform next moves from its position E to its position F, its condition at E being represented by Figures 12 and 13 and its condition at F being indicated by Figure 15. During this step, and consequently while the platform is in motion as indicated by the arrow in Figure 14, the folder arm 32 swings downwardly as shown in this figure and immediately afterward the folder arm 33 also swings downwardly. The result is that when the platform reaches the position F both of the folder arms 32, 33 are down in their lowermost positions.

The ejector hook 82 now pulls the finished package 96 off the platform, and off the turntable. This completes the operation.

I do not limit myself to the precise mechanism here shown and described, as variations may be made therein without departing from my invention, the scope of which is commensurate with my claims.

Having thus described my invention, what I claim as new and desire to secure by Letters Patent is as follows.

1. In a folding mechanism for packaging machines the combination, with a turntable, of a package wrapping platform carried by said turntable and provided with a portion for supporting a wrapper of sheet material and a cake of plastic material resting upon said wrapper, a pair of folder arms carried by said turntable and disposed upon opposite sides of said platform for the purpose of folding oppositely disposed edges of said wrapper, a pair of rocking shafts disposed upon opposite sides of said platform, each of said rocking shafts carrying one of said folder arms, a pair of pinions mounted upon said rocking shafts for actuating the same, a pair of racks each engaging one of said pinions, and mechanism connected with said racks and with said turntable, and controllable by the revoluble movement of said turntable, for actuating said racks one at a time.

2. In a folding mechanism for packaging machines, the combination, with a turntable, of a package wrapping platform carried by said turntable and provided with a portion for supporting said wrapper of sheet material and a cake of transient material resting upon said wrapper and adapted to be wrapped therein, a pair of rocking shafts journaled upon said turntable, a pair of folder arms mounted upon said rocking shafts and located upon opposite sides of said package wrapping platform for the purpose of folding oppositely disposed edges of said wrapper upon said cake of transient

material, a pair of pinions each mounted rigidly upon one of said rocking shafts, a pair of racks each engaging one of said pinions, a pair of separate actuating devices connected with said racks, and mechanism connected with said turntable and with said actuating devices, and driven by the rotation of said turntable, for energizing said actuating devices one at a time.

3. In a folding mechanism for packaging machines the combination of a turntable, a package wrapping platform carried thereby, a pair of rocking shafts journaled upon said platform, a pair of folder arms one mounted upon each shaft, a pair of sliding bars carried by said turntable, connections from said sliding bars to said rocking shafts for enabling said sliding bars to actuate said rocking shafts, a pair of rollers carried by said sliding bars and thus revoluble with said turntable, and a stationary cam provided with an inclined wall disposed partially within the path of travel of said rollers for the purpose of actuating said sliding bars, so that the revoluble movement of said turntable causes said rollers to reach said inclined portion of said cam wall at different moments of time.

4. In a folding mechanism for packaging machines the combination of a turntable, a package wrapping platform carried by said turntable, a pair of folder arms carried by said turntable and movable relatively to said platform for the purpose of folding the oppositely disposed edges of a wrapper over an article to be wrapped, a pair of rocking shafts connected with said folder arms for actuating the same, a pair of pinions carried by said shafts, a pair of sliding bars each provided with a portion formed into a rack and engaging one of said pinions, a bearing carried by said turntable and slidably supporting said sliding bars, a pair of rollers each carried by one of said sliding bars, and a stationary cam ring disposed adjacent said turntable and provided with an inclined wall disposed partially within the path of travel of each of said rollers, for the purpose of actuating said sliding bars.

5. In a folding mechanism for packaging machines the combination of a turntable provided with an opening, a bearing carried by said turntable and extending through said opening, a package wrapping platform carried by said turntable and disposed adjacent said bearing, said platform being provided with a portion for supporting a wrapper of sheet material and a transient article resting upon said wrapper, a pair of folder arms carried by said turntable and disposed upon opposite sides of said platform for the purpose of folding oppositely disposed edges of said wrapper upon said transient article, a pair of rocking shafts

disposed upon opposite sides of said platform, each of said rocking shafts carrying one of said folder arms, a pair of pinions mounted upon said rocking shafts for actuating the same, a pair of sliding bars extending through said bearing and each having a portion formed into a rack engaging

one of said pinions, and mechanism connected with said sliding bars and with said turntable, and controllable by the revoluble 10 movement of said turntable, for actuating said sliding bars one at a time.

FELIX WYNER.
